CARL W. BRENN, OF MONTCLAIR, NEW JERSEY, ASSIGNOR TO AUTOGRAPHIC REGISTER COMPANY, OF HOBOKEN, NEW JERSEY, A CORPORATION OF NEW JERSEY

MANIFOLDING

Application filed April 8, 1931. Serial No. 528,528.

This invention relates to manifolding, and more particularly, to the provision of a pile of superposed record and interleaved transfer strips for use in typewriting machines and the like.

Heretofore it was proposed to control the feeding of such a pile of manifolding strips in a typewriter by pin-wheels, and for this purpose the record strips were provided with rows of holes at their lateral edges for engagement by the pin-wheels which maintain the record strips in registration with each other and in alignment and in coordination with the feeding mechanism of the machine.

It was also proposed to reduce the number of papers engaging the pin-wheels by making the carbon strips narrow enough to lie entirely within the space between the pins on pin-wheels which are located at opposite ends of the platen, and with this arrangement it has been found advantageous to secure all the record and carbon strips together to travel through the typewriter or other machine as a unit.

An object of this invention is to provide for positively feeding both the carbon strips and the record strips by the feeding device of the typewriter or the like, and yet avoid the need of providing feeding bands on both edges of both the record strips and the transfer strips.

To this end, according to the present invention, the record strips and transfer strips are respectively off-set from each other laterally to provide feeding bands extending beyond the adjacent edges of the others and these feeding bands preferably are provided with a succession of pin-engaging apertures, the strips being secured together in this off-set relation by staples or other securing means passing through the superposed strips.

Besides saving material and work by obviating the need for a feeding band at both sides of each set of strips, an important advantage resulting from this arrangement is that the projecting portions of the respective strips constitute finger-grips by means of which the carbon sheets and record sheets

may be separately gripped and pulled apart to strip the one from the other after the strips have been severed along transversely extending registering lines of severance. Moreover, with this arrangement, one edge 55 of the record strips is not mutilated and the other edge having the pin-engaging apertures may be used as a binding edge when it is desired to bind the record sheets in a book.

In the preferred form of the invention, 60 each record strip, or at least the upper or "original" one, may be provided with longitudinally extending lines of weakness between the apertured feeding band and the main body of the strip along which the 65 strip may be torn to remove the feeding band therefrom if and when desired.

Also, the strips, especially the uppermost or "original" record strip, preferably has its unapertured lateral edge which is adjacent the apertured feeding band of the underlying strip located in close proximity to the pin-engaging apertures so that the strips, or, as stated, especially the upper record strip, will be held to the under-lying strips 75 by a part of the feeding mechanism which straddles the pins projecting through the pin-wheel apertures.

Other features and advantages will hereinafter appear.

In the accompanying drawings which illustrate one form of this invention, that at present preferred—

Figure 1 is a perspective view of a manifolding pack made in accordance with this 85 invention.

Fig. 2 is a plan view of a pile of strips corresponding to that shown in Fig. 1, and showing one set severed from the rest.

Fig. 3 is a perspective view showing the 90 transfer sheets in a severed set being stripped from the record sheets.

Fig. 4 is a plan view of the operating side of a transfer sheet forming part of one of the strips shown in Figs. 1 and 2, showing 95 how the feeding band thereon is left uncoated with transfer material.

Fig. 5 is a diagrammatic view showing a fragment of a typewriter platen with the feeding pin thereon, and the means which 100

straddles the pins engaging the margins of the uppermost record strip to hold it close to the underlying transfer strip.

As shown in the accompanying drawings, 5 the pile of manifolding strips may comprise record strips 10 with interleaved carbon strips 11 which are continuous in form and which are placed one above the other in superposed relation. For convenience, in shipping and handling, this pile of strips may be 10 zig-zag folded to form a pad or block 12 as shown in Fig. 1, from which the leading end may be lifted to be inserted in a typewriting machine or the like.

15 The zig-zag folding of the pile of strips 10 and 11 is facilitated by transverse weakening lines 13, preferably perforations, in some or all of the strips and these further serve as 20 lines of severance along which the pile of strips may be severed to form sets of interleaved record sheets 10a and carbon sheets 11a.

25 In cases where it was desired to use the pile of strips 10 and 11 in a telegraphic typewriter having pin-wheel feeding devices for keeping the pile in strict coordination with the platens of the sending and receiving machines, it was heretofore customary to provide the record strips 10 with lateral margins 30 projecting beyond the adjacent edges of the carbon strips so as to constitute feeding bands having apertures for engaging pins 14 on the typewriter platen 15, see Fig. 5.

35 Instead of providing the record strips 10 with lateral margins at both sides to form feeding bands, they are according to the present invention, provided at only one side with a feeding band 16 while the transfer strips 11 at the other lateral edge of the pile of 40 strips is provided with feeding bands 17.

45 This is accomplished by off-setting the transfer strips 11 from the record strips 10 laterally and the strips are maintained in this lateral off-set relation by securing means such as staples 18 preferably located on the 50 lines of severance 13 so as to become inoperative to hold the strips together when the strips are severed along said lines of severance 13 to form record sheets 10a and transfer sheets 11a, see Fig. 2. In this way, the amount of material needed to produce the pack is reduced by omitting and obviating the need for the feeding band at both sides of the record or transfer strips.

55 In addition to this, the provision of the feeding bands on the record strips and transfer strip respectively at opposite lateral edges of the pile permits the feeding bands to constitute finger grips by means of which the record sheets 11a may be gripped with the fingers of one hand while the transfer sheets 11a may be gripped with the fingers of the other hand so that upon drawing the hands apart the transfer and record sheets are stripped 60 from each other as indicated in Fig. 3.

When the manifolding pile of the present invention is to be employed, with the telegraphic typewriter or other machine having pin-wheel feeding devices, the feeding bands 16 and 17 are each provided with apertures 70 19 extending in rows longitudinally thereof. These apertures substantially fit the feeding pins 14, see Fig. 5.

The feeding band 16 on the record strip may be divided from the main body of the 75 strip by a longitudinally extending weakening line 20, and this arrangement is especially advantageous when employed on the uppermost or "original" record strip; for, when desired, the feeding band 16 may be torn 80 from the main body of the record sheet 10a along the weakening line 20 so that the record sheet will be a plain rectangular sheet. If desired, however, the feeding band 16 may be left on the record sheet and may be used 85 to clamp the record sheet in a loose-leaf or other binder which may, if desired, have rings or pins for engaging the holes 19 therein.

90 Preferably, the record strips 10 and transfer strips 11 are off-set laterally only sufficient to permit the pins 14 to pass through the holes 19 without engaging the adjacent edges 21 of the other set of strips, so that a grooved roller 22 provided on the machine with which the pile of strips is to be used may 95 straddle the pins 15 and engage the edge 21 of the inwardly off-set strips and hold the strips against falling away from the typewriter platen 15. This is especially true of the top 100 or "original" record strip 10 and is not of such great importance in accordance with the under strips, for, if the top strip is held against falling away from the platen, the others will be held in place by the top strip.

105 While the record strips 10 and transfer strips 11 are substantially of the same width, for economy sake the transfer strips may be made narrower than the record strips so as to only underlie the printed portions of the record strips and thus may have their 110 unapertured edges 23 fall short of the lines of weakness 20 in the record strips, as indicated in Fig. 2.

115 As shown in Fig. 4, the transfer sheets 11a may be only partially covered with transfer material, approximating that area normally typed upon in the record sheet 10a, to thus provide a clean finger grip area for the operator when stripping the transfer sheets from the record sheets.

120 No claim is made in this application to a pile of continuous strips with interleaved carbon strips fastened together with staples or other fastening means located through the strips on the line of perforations, for this subject matter is disclosed and claimed in my copending application Serial No. 221,912 filed September 26, 1927.

125 The feature of having the edges of the carbon strips inwardly removed from the adja-

- cent edges of the record strips, and of having the edges of the carbon strips tangential to the pin-wheel apertures is disclosed and claimed in my copending application Ser. 5 No. 401,897 filed Oct. 23, 1929, which is a division of my application Ser. No. 335,402 filed Jan. 28, 1929.
- Variations and modifications may be made within the scope of this invention and 10 portions of the improvements may be used without others.
- Having thus described the invention, what is claimed as new and for which it is desired to obtain Letters Patent, is:—
- 15 1. A connected pile of superposed record strips and interleaved transfer strips, the latter having at one side only feeding bands projecting beyond the adjacent edges of the record strips, the record strips having at one 20 side only feeding bands projecting beyond the adjacent edges of the transfer strips.
2. Superposed record strips and interleaved transfer strips for use with feed regulating pin-carrying devices, the record 25 strips and transfer strips being off-set laterally and respectively projecting beyond the adjacent edges of the other and having each a row of pin-wheel apertures in said projecting portions, and means securing the record 30 and transfer strips together in lateral off-set relation.
3. A connected pile of superposed record strips and interleaved transfer strips, all of substantially the same width, divided at intervals by registering transverse lines of severance, the record strips and the transfer strips being off-set laterally relative to each other and projecting beyond the other to form finger grips for use in stripping the 35 record strips from the transfer strips after the said strips have been severed along said registering transverse lines of severance.
4. A connected pile of superposed record strips and interleaved transfer strips, the latter 40 having at one side only feeding bands projecting beyond the adjacent edges of the record strips, the record strips having at one side only feeding bands projecting beyond the adjacent edges of the transfer strips.
- 45 5. A connected pile of superposed record strips and interleaved transfer strips, the latter having at one side only feeding bands having each a row of pin-wheel engaging apertures, the edges of the strips adjacent the projecting edges being located in close proximity to the rows of pin-wheel engaging apertures in the feeding bands.
- 60 6. A connected pile of superposed record strips and interleaved transfer strips, the latter having at one side only feeding bands projecting beyond the adjacent edges of the record strips, the record strips having at one side only feeding bands projecting beyond the adjacent edges of the transfer strips, said feeding bands having each a row of pin-wheel 65 engaging apertures, and longitudinally ex- tending lines of weakness between the feeding band on at least one of the record strips and the body of said record strips along which the record strip may be torn to remove the apertured feeding band from the body 70 of the strips.
6. A connected pile of superposed record strips and interleaved transfer strips, the latter having at one side only feeding bands projecting beyond the adjacent edges of the record strips, the record strips having at one side only feeding bands projecting beyond the adjacent edges of the transfer strips, said feeding bands having each a row of pin-wheel 75 engaging apertures, the edge of the uppermost record strip adjacent the feeding band on the under-lying carbon strip being located in close proximity to the row of apertures in the latter to be engaged and held to the underlying transfer strip by means 80 straddling the pins extending through said apertures.
7. A pile of superposed record strips and interleaved transfer strips, the latter having at one side only feeding bands projecting beyond the adjacent edges of the record strips, the record strips having at one side only feeding bands projecting beyond the adjacent edges of the transfer strips.
8. A pile of superposed record strips and interleaved transfer strips, the latter having at one side only feeding bands projecting beyond the adjacent edges of the record strips, the record strips having at one side only feeding bands projecting beyond the adjacent edges of the transfer strips, the feeding bands 90 of the record strips having pin-wheel engaging apertures.
9. A pile of superposed record strips and interleaved transfer strips, the latter having at one side only feeding bands projecting beyond the adjacent edges of the record strips, the record strips having at one side only feeding bands projecting beyond the adjacent edges of the transfer strips, the feeding bands 95 of the record strips having pin-wheel engaging apertures.
10. A pile of superposed record strips and interleaved transfer strips, the latter having at one side only feeding bands projecting beyond the adjacent edges of the record strips, the record strips having at one side only feeding bands projecting beyond the adjacent edges of the transfer strips, the feeding bands 100 of the record strips and in the transfer strips having pin-wheel engaging apertures.
11. A pile of superposed record strips and interleaved transfer strips, the latter having at one side only feeding bands projecting beyond the adjacent edges of the record strips, the record strips having at one side only feeding bands projecting beyond the adjacent edges of the transfer strips, the feeding bands 105 of the carbon strips having pin-wheel engaging apertures.

ing apertures, the edges of the record strips being substantially tangential to the apertures in the carbon strips.

Signed at Hoboken, in the county of Hudson, and State of New Jersey, this 1st day of April, 1931.
